CARL R. DAELLENBACH, OF ELLWOOD CITY, PENNSYLVANIA, ASSIGNEE OF ONE-HALF
TO HARRY H. HANCHER, OF ELLWOOD CITY, PENNSYLVANIA.

VACUUM SYSTEM.

1,298,903.

Specification of Letters Patent. Patented Apr. 1, 1919.

Application filed April 9, 1917. Serial No. 180,770.

To all whom it may concern:

Be it known that I, CARL R. DAELLENBACH, citizen of the United States, residing at Ellwood City, in the county of Lawrence 5 and State of Pennsylvania, have invented certain new and useful Improvements in Vacuum Systems, of which the following is a specification.

My invention relates to means for feeding 10 liquid fuel from a supply tank to a carbureter of an internal combustion engine.

The principal object of the invention is to raise the liquid fuel from a lower point to a higher point so that the liquid may be 15 fed by gravity to the engine from this higher point.

Another object of the invention is to lift the liquid by a vacuum created by the action of the engine.

20 A further object of the invention is to provide positive means for breaking the vacuum when enough fuel has reached the receptacle at the higher point, so as to permit the fuel at this point to feed to the engine by gravity.

Another object of the invention is to automatically re-create the vacuum in the receptacle when the same is practically empty of fuel.

30 Another object is to provide means for causing an uninterrupted flow of fuel to the carbureter while the vacuum is set up and is causing the fuel to rise in the receptacle.

The invention also consists in certain 35 other features of construction and in the combination and arrangement of the several parts to be hereinafter more fully described and specifically pointed out in the appended claims.

40 In describing my invention in detail, reference will be had to the accompanying drawings, wherein like characters denote like or corresponding parts throughout the several views and in which:

45 Figure 1 is a longitudinal sectional view through the device.

Fig. 2 is a section on line 2—2 of Fig. 1.

Referring to the drawings, 1 indicates the receptacle, provided with a cover 2 and a conical bottom 2'. This receptacle is connected with the usual storage tank by means 50 of the pipe 3 and the check valve 4. It is also connected with the carbureter by means of the pipe 5 having a check 6 connected thereto by the coupling 7. The upper part 55

of the receptacle is connected with the intake manifold of the engine by means of the pipe 8 connecting with the port 9 in the head 2, said port 9 communicating with a circular port 10 opening into the receptacle. 60

In the conical bottom 2' I locate a drain cock 11. 12 is a guide rod, movably mounted in the receptacle by means of a bracket 13 located on the bottom 2', and at its upper end said guide rod passes through a 65 sleeve 2" formed on the cover and acting as a guide for the said rod 12. Said sleeve has an air port 2" therein, communicating with the interior of the receptacle as shown.

A dust cover 14 located on the sleeve prevents 70 dust and the like from entering the air port. 15 is a float guided on the rod 12 and having a counter-balance cup 16 at its lower end. 17 is a stop formed adjacent the lower end of the rod 12, and 18 is a combined stop and valve located adjacent its upper end, said rod also having an enlargement 75 19 forming a valve for the air port 2".

20 is a vent connecting with the check valve 6 and extending well above the top 80 of the receptacle, said vent having a valve seat 20' with which the ball 6' of the check valve 6 is adapted to engage. 21 is a priming plug located in the head 2.

The device operates as follows: The receptacle being empty and all the pipes properly connected, when the engine is started, the suction created thereby acting through the pipe 8 and ports 9 and 10 will create a 85 vacuum in the receptacle, thus causing the liquid fuel to flow from the storage tank through pipe 3 and check 4 into the receptacle.

The fuel rising in the receptacle will cause the float 15 to rise on the bar 12, it being 90 understood that the liquid as it rises will fill the counterbalance cup 16. When the top of the float strikes the stop 18, it will carry the rod 12 with it so as to bring the valve 18' forming part of the stop 18, against the top 100 of the receptacle 2 so as to close the port 10 and thus shut off the suction. At the same time the valve 19 uncovers the port 2", so as to admit air into the receptacle and thus break the vacuum therein. This will allow 105 the liquid to flow by gravity through the check 6 and pipe 5 to the carbureter. As the level of fuel in the receptacle lowers the float 15 drops, though the rod 12 is held up by reason of the suction in the port 10 acting 110

against the valve 18'. When the receptacle is practically empty the counterbalance cup 16 strikes the stop 17 and by reason of the weight of this cup with the fuel therein the rod 12 is lowered so as to uncover the port 10 and close the port 2^a. Thus the vacuum is set up again and the receptacle is again filled as before.

By reason of the vent 20, the fuel in the pipe 5 will continue to feed to the carburetor, though the valve 6 is closed, by reason of the vacuum in the receptacle, it being understood that there will be enough fuel in the pipe 5 to run the engine until the receptacle is full and feeding of the fuel to the pipe 5 begins again. As will be noted, the conical bottom 2' forms a sediment chamber and this can be cleaned out by means of the cock 11.

It is thought from the foregoing that the advantages and novel features of my invention will be readily apparent.

I desire it to be understood that I may make slight changes in the construction and in the combination and arrangement of the several parts, provided such changes fall within the scope of the appended claims.

I claim as my invention:

1. A vacuum feeding system comprising a receptacle connected to the storage tank and with the intake manifold of the engine to create a vacuum in the receptacle to cause fuel to flow into the receptacle from the tank, a rod slidably mounted in said receptacle, a valve thereon controlling the connection with the manifold, upper and lower stops on said rod, a float slidably mounted

upon said rod, and a receptacle always containing fuel to constitute a weight connected to said float and slidably mounted upon said rod for transmitting movement to said rod when the liquid in the first named receptacle attains a low level and the second named receptacle engages with the lowermost stop to move said valve away from the connection with the manifold, for setting up another vacuum.

2. A vacuum feeding system comprising a receptacle connected to the storage tank and with the intake manifold of an engine, a float in said receptacle, means operated by the float for controlling the connection with the manifold, a valve casing secured to the lower side of said receptacle, a valve seat in said casing, a ball valve in said casing, an outlet pipe connected to the side of said casing adjacent the valve seat and connecting said receptacle to the carburetor, a vertical vent pipe secured to the top of said valve casing and having a valve seat to receive said ball valve when the receptacle is filled, and said valve seat of the valve casing being adapted to receive said ball valve while a vacuum is being created in the receptacle so as to open said vent pipe to permit free air to force the fuel in the outlet pipe into the carburetor.

In testimony whereof I affix my signature in presence of two witnesses.

CARL R. DAELLENBACH.
